UNITED STATES PATENT OFFICE.

RALPH H. FOSTER, OF JERSEY CITY, NEW JERSEY.

DESIGN FOR A BOTTLE-OPENER AND BUTTON-HOOK.

44,839.

Specification for Design.

Patented Nov. 4, 1913.

Application filed January 15, 1913. Serial No. 742,285. Term of patent 7 years.

To all whom it may concern:

Be it known that I, RALPH H. FOSTER, a citizen of the United States, residing at Jersey City, in the county of Hudson and State of New Jersey, have invented a new, original, and ornamental Design for a Bottle-Opener and Button-Hook, of which the following is a specification, reference being had to the accompanying drawing, forming a part thereof.

The figure is a side elevation of a combination bottle opener and button hook embodying my new design.

I claim:

The ornamental design for a bottle opener and button hook, as shown.

RALPH H. FOSTER.

Witnesses:

JOHN J. MAHONEY,
AUGUST MUELLER.
